CLAIM

The ornamental design for a combined solenoid housing and cable linkage, as shown and described.

DESCRIPTION

FIG. 1 is perspective view of the combined solenoid housing and cable linkage showing my new design;
FIG. 2 is a front elevational view thereof;
FIG. 3 is a rear elevational view thereof;
FIG. 4 is a top plan view thereof;
FIG. 5 is a bottom plan view thereof;
FIG. 6 is a side elevational view thereof; and,
FIG. 7 is an elevational view of the side of the Solenoid Housing opposite to that shown in FIG. 6.

FIG. 2

FIG. 3

FIG. 4
